United States Patent Office

Des. 187,576
Patented Mar. 29, 1960

187,576

LAWN SPRINKLER HEAD

Frederick David Chapman, Chicago, Ill., assignor to Scovill Manufacturing Company, Waterbury, Conn., a corporation of Connecticut

Application January 10, 1958, Serial No. 49,195

Term of patent 7 years

(Cl. D91—1)

Fig. 1

Fig. 2

Fig. 3

Fig. 1 is a perspective view of a lawn sprinkler head embodying my new design.

Fig. 2 is a top plan view thereof.

Fig. 3 is a front elevation thereof, and

Fig. 4 is an end elevational view thereof.

I claim:

The ornamental design for a lawn sprinkler head, substantially as shown.
